DESIGN FOR A JEWELRY STONE SETTING

David Klebanoff, New York, N. Y., assignor to David Klebanoff and Samuel Grossman, copartners, doing business as Klebanoff and Grossman, New York, N. Y.

Application September 26, 1935, Serial No. 58,720

Term of patent 7 years

To all whom it may concern:

Be it known that I, David Klebanoff, a citizen of the United States of America, residing at the city of New York, county of Bronx, and State of New York, have invented a new, original, and ornamental Design for a Jewelry Stone Setting, of which the following is a specification, reference being had to the accompanying drawing, forming part thereof.

Fig. 1 is a top plan view of a jewelry stone setting showing the new design; and

Fig. 2 is a side elevation thereof.

I claim:

The ornamental design for a jewelry stone setting as shown.

In witness whereof I have signed this specification this 23d day of September, 1935.

DAVID KLEBANOFF.
